Primary Examiner — Karen E Kearney*Assistant Examiner* — Carissa C Fitts(74) *Attorney, Agent, or Firm* — Foley & Lardner LLP(57) **CLAIM**

I claim the ornamental design for a portable light, as shown and described.

DESCRIPTION

FIG. 1 is a perspective view of a portable light of the claimed design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines show portions of the article not claimed and form no part of the claimed design.

1 Claim, 7 Drawing Sheets(56)
